SUPPORT MEANS FOR VERTICALLY SLIDABLE WINDOWS, DOORS, AND THE LIKE

Lawrence Basil Lambert and Robert William Orange, Auckland, New Zealand

Application July 11, 1947, Serial No. 760,438
In New Zealand August 14, 1944Section 1, Public Law 690, August 8, 1946
Patent expires June 25, 1965

1 Claim. (Cl. 292—16)

1

This invention relates to vertically slideable windows, doors and the like and has for its objects the provision of improved means applied to the windows, doors and the like for the support thereof in the window or door frame, such support means enabling the window or door to be retained in any open position as desired; substantially eliminating any tendency to rattle; enabling easy adjustment, repair or replacement if and when required, and being of a compact form whereby the window or door frame is appreciably simplified.

At present in respect of vertically slideable type windows or doors, sash weights and cords are applied to each side edge of the window or door, the weights being housed within cavities within the window or door frame, these window frames requiring to be extra wide and heavy especially if of the double frame type for the housing of the weights and in the event of a sash cord breaking, considerable dismantling of the woodwork is involved in order that a repair be effected, windows and doors of this type being also notorious for rattling.

By our invention improved support means are provided which are completely housed within the window or door and require no special provision in respect of the frame, which is thereby appreciably simplified in construction and reduced in bulk, the windows or doors themselves requiring only a simply effected alteration in order that they be able to house the support means.

Broadly the invention comprises improved support means for vertically slideable windows, doors and the like wherein the support means are housed within slots or channels formed in the side edges of said windows or doors, said support means comprising bow spring means secured within the slots or channels and adapted to curve towards the outside thereof, said bow springs carrying ramp means on which are slidably mounted shoe means for bearing against the window or door frame, means being provided whereby the extent of pressure applied by the shoes to the window or door frame is adjustable.

In describing the invention reference will be made to the accompanying drawings in which:

Figure 1 shows a sectional side elevation of a window or sash and its frame with the support means applied.

2

Figure 2 is an end elevation of the window.

Figure 3 shows an enlarged elevation of the lower end of the support unit.

Figure 4 shows the position of the shoes while 5 the window or sash is being moved upwardly in its frame.

Figure 5 is a sectional plan view of the edge of the window showing the projection of the shoe.

In the invention, the only required alteration 10 to the window sash 1 (or door) is the provision of a slot or channel 2 in each of its two vertical side edges 3 which are adjacent to the window or door frame 4, the support units 5 being housed within the slots or channels 2 and completely 15 hidden.

These support units 5 comprise in the preferred form, upper and lower bow springs 6 and 7 secured together at their inner ends to a rigid non-bendable connecting bar 8 of preferably 20 channel cross section which will be a neat but slideable fit within the channel 2, the outer end of the upper bow spring 6 being anchored to the window 1 as by a screw 9 and the outer end of the lower bow spring 7 also anchored, but in an 25 adjustable manner by being riveted to a rigid base strip 10 (see Fig. 3) which makes a neat but slideable fit in the channel 2 and has a right angle bend 10a through which an adjustment screw 11 freely passes, such adjustment screw 11 screwing 30 through a crossbar or pin 12 which will be engaged in the window to extend across the slot or channel 2 therein.

The adjustment screw 11 will preferably but not necessarily have a sleeve or distance piece 13 fitted thereon between its head and the base strip portion 10a, this being for the purpose of enabling the head of the screw 11 to extend to a position near the open bottom end of the slot or channel 2 for readily accessible adjustment purposes.

To the outer or convex sides of each of the upper and lower bow springs 6 and 7 there are shoe carrying ramps 14 and 15, these each being formed of bent rod or like riveted 16 to the bow spring and having a free lower end 17 which is 45 slideable through a hole 18 in an angle bracket 19 secured as by a rivet 20 to the bow spring.

Slidably mounted on each of the ramps 14 and 15 there is a contacting shoe 21 which presents a flat face 21a adapted to extend beyond the side 50 edge 3 of the window and to bear against the

frame 4, these shoes 21 preferably having shoulders 21b (see Fig. 5) to limit extent of inward movement thereof into the channel 2 and being slidable on the ramps 14 and 15 by having journals 21c slidable on the latter, light compression springs 22 being disposed over the ramps 14 and 15 between the shoes 21 and the angle brackets 19 to yieldingly tend to move the shoes 21 to the upper position as shown in Figs. 1, 2 and 3.

The window sash 1 will be retained in or guided against the window frame 4 by the usual removable bullnose or like strip or batten 23 secured to the said frame 4 (see Fig. 5).

While it is preferred to have a support unit 5 combining upper and lower bow springs 6 and 7 with their respective ramps 14 and 15 and shoes 21, it will be obvious that there could be two units to each window side edge each composed of one bow spring, ramp and shoe and each separately anchored by a screw and having an outwardly disposed adjustment screw.

The spring action of the bow springs 6 and 7 is such as to naturally tend to move the shoes 21 outwardly from the edge 3 of the window 1 (or door) so that these shoes 21 will press against the frame 4 to a moderate extent which however is capable of being increased or decreased by movements of the adjustment screws 11.

For general window or door purposes, two complete units 5 (one unit in each side edge) will be ample to effect the desired support as presenting two shoes bearing on each side of the frame, but in the case of exceptionally heavy windows or doors, units could be provided having more than the two shoes each with corresponding bow springs.

In use or operation, the window or door 1 as the case may be, may be provided at the factory with the units 5 fitted thereto, or if desired the units could be fitted to existing windows provided same are removed and the channels 2 formed therein, the frame 4 requiring no special provision for receiving the window or door.

To fit the window 1, the usual bullnose strip or like 23 is removed, thereby allowing insertion of the window in a normal manner except in that the shoes 21 may offer some slight yielding resistance, the bullnose strip 23 being then replaced to thereby act as the retaining guide to permit of vertical guided movements of the window.

In accordance with the weight of the particular window or door, the degree of pressure the shoes 21 will apply to the frame 4 is variable by test, and if the window will not stay up when pushed up, the adjustment screws 11 of the units 5 are adjusted to cause them to move towards the fixed crossbar or pin 12, this having the effect of moving the rigid base strip 10 inwardly, incidentally shortening the distance between the outer ends of the bow spring 6 and 7 so that they tend to curve outwardly to an increased extent, but being unable to do this, they transmit increased outward pressure on the shoes 21 so that the latter increase their pressure on the frame 4 to an extent which by the adjustment, will be just sufficient to enable the window to remain held or supported in desired open positions, but not so great as to prevent reasonable downward pres-

sure from being all that is required to close the window.

To open the window from the downward closed position, it will be obvious that (contrary to sash weight windows wherein the sash weight substantially counterbalances the weight of the window) it is necessary to lift the full weight of the window and but for the provision of the ramps 14 and 15, such weight plus resistance to movement caused by the shoes would be excessive.

However, when the window is to be raised, such upward movement thereof in the initial stages will cause the shoes 21 to lag behind to an extent which will be equivalent to the extent of movement the shoes 21 are capable of making on their ramps 14 and 15 in compressing the light compression springs 22.

This travel of each shoe 21 along its ramp 14 or 15 from the highest to a lower position thereon (as shown in Fig. 4) causes a great easing of the pressure applied by the bow springs 6 and 7 to their respective shoes 21 and thus the window is substantially easily lifted, but when released, falls to the small extent required to cause the shoes 21 to be moved on their ramps 14 and 15 back to the normal position as shown in Fig. 3, whereby full pressure is re-transmitted to the shoes 21 so that they resist downward movement of the window.

Obviously the shoes 21 will never release their application of pressure on the window or door frame 4 and thus the window or door will never have any degree of slack in its mounting to the frame to enable it to rattle.

We claim:

Improved support means for vertically slidable windows, doors and the like comprising a support unit having two bow springs secured together at their inner ends by a non-bendable connecting bar, the outer end of one bow spring being secured as by a screw to the window or door and the outer end of the other bow spring secured to a rigid base strip, an adjustment screw passing freely through a right angle bent portion of the base strip and screwing through a crossbar or pin which is secured to the window or door to extend across the slot or channel thereof, ramps of bent rod riveted to the outwardly curved faces of the bow springs and having their free ends slidably fitted through angle brackets also secured to the bow springs, shoes slidable on the ramps and compression springs on said ramps adapted to yieldingly move the shoes to the higher portions of said ramps substantially as described and for the purposes set forth.
